US0D1027670S

(12) **United States Design Patent** (10) Patent No.: **US D1,027,670 S**
(45) Date of Patent: ** May 21, 2024

(54) **WATCH**

(71) Applicant: **Dion Consulting GmbH**, Löningen (DE)

(72) Inventor: **Vitali Jeschow**, Löningen (DE)

(**) Term: **15 Years**

(21) Appl. No.: **35/516,246**

(22) Filed: **Oct. 25, 2022**

(80) **Hague Agreement Data**

Int. Filing Date: **Oct. 25, 2022**

Int. Reg. No.: **DM/226454**

Int. Reg. Date: **Oct. 25, 2022**

Int. Reg. Pub. Date: **Feb. 10, 2023**

(51) **LOC (14) Cl.** 10-02

(52) **U.S. Cl.**

USPC **D10/39**
